UNITED STATES PATENT OFFICE.

JACOB MARTIN NABSTEDT, OF DAVENPORT, IOWA.

DESIGN FOR A BADGE.

SPECIFICATION forming part of Design No. 31,342, dated August 8, 1899.

Application filed July 3, 1899. Serial No. 722,761. Term of patent 7 years.

To all whom it may concern:

Be it known that I, JACOB MARTIN NABSTEDT, a citizen of the United States, residing at Davenport, in the county of Scott and State 5 of Iowa, have invented and produced a new and original Design for a Badge, of which the following is a specification, reference being had to the accompanying drawings, forming part thereof.

10 Figure 1 is a plan view showing the face of my new design. Fig. 2 is a sectional view of the design in relief on the line X X of Fig. 1, as shown in the drawings.

15 The leading and material feature of my design consists of a badge having a central figure of "Herman the Cherusker," with winged helmet, round shield at side on left arm, the right arm upraised and holding aloft a two-edged sword, and this figure surmounted 20 by an eagle with outspread wings and bearing in its talons, which are concealed thereby, a United States shield. At both sides of the

central figure and forming the sides of the design is a scroll, the middle of which passes behind and is concealed by the feet and legs 25 of the central figure. The space between the central figure and the scroll is occupied by an inner scroll and background, as shown by Fig. 1. Fig. 2 shows the elevation of the outer scroll A A and the central figure B, which 30 is same as for the head, breast, and upper part of the wings of the eagle and the shield.

It is apparent that this design is also applicable to other similar articles.

Having described my invention, what I 35 claim as new, and desire to secure by Letters Patent, is—

The design for a badge, as herein shown and described.

JACOB MARTIN NABSTEDT.
